UNITED STATES PATENT OFFICE.

KELLEY MONROE TURNER, OF JAMAICA, NEW YORK, ASSIGNOR TO GENERAL ACOUSTIC COMPANY, A CORPORATION OF NEW YORK.

DESIGN FOR A TELEPHONIC TRANSMITTING APPLIANCE.

47,905.

Specification for Design.

Patented Sept. 28, 1915.

Application filed March 20, 1912. Serial No. 685,067. Term of patent 14 years.

To all whom it may concern:

Be it known that I, KELLEY MONROE TURNER, a citizen of the United States, residing at Jamaica, in the county of Queens and State of New York, have invented a new, original, and ornamental Design for a Telephonic Transmitting Appliance, of which the following is a specification, reference being had to the accompanying drawing, in which—

Figure 1 is a front view of a telephonic transmitting appliance illustrating my new design, Fig. 2 is a side elevation, and Fig. 3 a rear view.

The design relates to the form or configuration of the instrument and the sound openings thereof.

The drawing shows a rear view, a side view and a front view of a telephonic transmitting appliance embodying the design.

Copies of this patent may be obtained for five cents each, by addressing the "Commissioner of Patents, Washington, D. C."

The instrument is made with a flat front face with a middle portion having two parallel straight sides and semi-circular ends, also having a double series of elongated slightly curved slots arranged as clearly shown in the drawing, the back of the instrument being made with a deep bevel or chamfer giving it the appearance of comparative thinness so as to be neat and inconspicuous when worn on a man's coat or lady's waist.

I claim,—

The ornamental design for a telephonic transmitting appliance as shown and described.

KELLEY MONROE TURNER.
